UNITED STATES PATENT OFFICE.

JOSEPH O. CLARK, OF BOSTON, MASSACHUSETTS, ASSIGNOR TO THE PHOENIX MANUFACTURING COMPANY, OF SOUTH BERWICK, MAINE.

CURTAIN-ROD FIXTURE.

SPECIFICATION forming part of Letters Patent No. 640,993, dated January 9, 1900.

Application filed May 19, 1899. Serial No. 717,419. (No model.)

To all whom it may concern:

Be it known that I, JOSEPH O. CLARK, a citizen of United States, residing at Boston, in the county of Suffolk and State of Massachusetts, have invented certain new and useful Improvements in Curtain-Rod Fixtures, of which the following is a specification, reference being had therein to the accompanying drawings.

10 Figure 1 is a perspective view of a curtain-pole fitted with my new fixture and secured in place, the pole being shown in dotted lines. Fig. 2 is a side view of my new fixture. Fig. 3 is a plan view of my new fixture.

15 The object of my invention is to provide a fixture for poles for curtains, portières, and the like which is simple and efficient and which obviates the use of screws, nails, and like securing means which deface the walls and casing. The use of non-slipping material to retain the fixture and pole in place is a feature of my invention.

20 In the drawings illustrating the principle of my invention and the best mode now known to me of applying that principle, *a* is a ring which passes over the end of the pole *b*, to which it is secured by the set-screw *c*. Fast at one end to the ring *a* is an arm *d*, on the other end of which is formed a pointed hook *e*, that engages the casing *f*. Fast to the ring *a* is a flat spring *g*, the free end of which is provided with a covering of non-slipping material *h*.

25 To secure a curtain-pole in place by means of my new fixture, the end of the pole is passed through the ring *a*, which is then secured in its proper position by the set-screw *c*. The position in which the ring is secured is such that it is necessary to bend outwardly the 30 spring *g* in order that the spring *g* may pass

by the casing *f*. The tension of the spring is thus brought into play, and the free end of the spring and its non-slipping covering are pressed against the casing. The pointed hook *e* is forced down on or into the top of the casing. 45

It is obvious that the ring *a* may be driven on the pole into adjusted position, if so desired, and that in such case the set-screw *c* or other independent mechanism for fastening the ring in place may be dispensed with. 50

My fixture is very simple and cheap and entirely does away with the use of screws and nails which are ordinarily used to secure brackets and which permanently deface the walls. 55

What I claim is—

1. As a new article of manufacture, the improved curtain or like rod fixture, the same comprising a pole-ring; an attached spring which extends away from a side of the ring; 60 non-slipping material on the inner side of the free end of the spring; and a hook which extends from the ring upwardly and has its free end above the inner side of the free end of the spring. 65

2. The combination of a curtain or like pole with a ring; and means for securing the ring on the pole; the ring having a spring extending away from a side of the ring; non-slipping material secured on the inner side of the 70 free end of the spring; and a hook which extends from the ring upwardly and has its free end above the inner side of the free end of the spring.

In testimony whereof I affix my signature 75 in presence of two witnesses.

JOSEPH O. CLARK.

Witnesses:

EDWARD S. BEACH,
E. A. ALLEN.
